BASEBALL CAP

Stuart R. Thornton, 3700 26th St., San Francisco, Calif.

Filed Nov. 2, 1964, Ser. No. 82,419

Term of patent 14 years

(Cl. D3—13)

FIG. 1

FIG. 2

FIG. 3

FIG. 4

FIG. 5

FIG. 1 is a front view, showing the baseball cap of my invention;

FIG. 2 is a back view of FIG. 1;

FIG. 3 is a side view of FIG. 1, the side opposite thereto being a mirror image thereof;

FIG. 4 is a top view of FIG. 1; and

FIG. 5 is a bottom view of FIG. 1.

I claim:

The ornamental design for a baseball cap, as shown and described.
